UNITED STATES PATENT OFFICE.

MARVIN A. SHARP AND BIRD H. SHARP, OF LAPORTE, TEXAS.

WIND-WHEEL.

SPECIFICATION forming part of Letters Patent No. 787,346, dated April 11, 1905.

Application filed December 19, 1903. Serial No. 185,851.

To all whom it may concern:

Be it known that we, MARVIN A. SHARP and BIRD H. SHARP, citizens of the United States, residing at Laporte, in the county of Harris 5 and State of Texas, have invented new and useful Improvements in Wind-Wheels, of which the following is a specification.

This invention relates to windmills; and the primary object of the same is to provide the 10 curved blades or vanes with means of an advantageous nature which will produce an automatic operation to position the said blades or vanes to the best advantage in relation to a current of wind and also to so connect the 15 curved blades to a shaft that a strong and durable structure will result.

A further object of the invention is to include in connection with a windmill-shaft and pump-rod simple means for regularly reciprocating said rod.

The invention consists in the construction and arrangement of the several parts, which will be more fully hereinafter set forth.

In the drawings, Figure 1 is an elevation 25 of the upper part of a windmill-shaft and a curved blade or vane embodying the features of the invention. Fig. 2 is a top plan view of a cam-wheel secured on the shaft for operating the pump-rod. Fig. 3 is a top plan 30 view of the windmill, showing the radial disposition of the blades or vanes.

Similar numerals of reference are employed to indicate corresponding parts in the several views.

35 The numeral 1 designates a shaft of any suitable length having on the upper extremity thereof two hub-disks 2 and 3, the lower disk 2 being of materially larger dimensions than the upper disk to adapt it to support a greater 40 portion of the weight of the curved blades or vanes which are connected thereto. Projecting outwardly from the hub-disks 2 and 3 are arms 4 and 5, the arms 5 of the disk 3 being longer than the arms 4 and disposed at an 45 upward angle of inclination for attachment to curved blades at a proper point. Only one blade 6 is shown, and projecting from the inner edge thereof are upper and lower hinge-straps 7 and 8, respectively, pivoted or mov- 50 ably coupled to the outer extremities of the

arms 4 and 5. The arms 4 and 5 may be termed "fulcrum-arms," on which the blade 6 is shown, and said arms will extend outwardly from the disks 2 and 3 at regular intervals and be attached to the hinge-straps of other blades, as just explained. Secured to the central portion of one side of the blade or vane 6 is a connecting-rod 9, having its inner end movably attached to the upper end of a lever 10, fulcrumed on the arm 4, and having a weight 11 adjustably held on the lower extremity thereof and retained in place by means of a set-screw 12.

The connecting-rod and lever 10, with its weight 11, form a counterpoise means which 65 operates to hold the blade in normal position and adds to each blade sufficient resistance to withstand movement on the fulcrum devices therefor under the force of ordinary wind-currents. In the event that these currents 70 increase in pressure intensity the blade will be thrown around or move on its fulcrum means and pull the lever 10 so that the lower weighted end thereof will be thrown outwardly, and the moment that the wind force 75 is reduced to such an extent as to permit the counterpoise means to operate the latter will draw the blade back to normal position. This automatic adjustment will be found materially 80 advantageous in windmill structures, especially as it obviates any tendency toward breakage of the blades under abnormally high air-pressure.

On the shaft 1, at a suitable elevation, a cam-wheel 13 is secured and has the periphery 85 thereof provided with convolutions 14, which give the rim of the wheel an elevated position at one point and a depressed position at a diametrically opposite point. The upper end of the pump-rod 15 has pins 16 projecting 90 inwardly therefrom, on which are disposed rollers 17, held in close contact with the upper and lower edges of the rim of the wheel 13, and as the latter is operated the pump-rod 95 will have imparted thereto a regular vertical reciprocation.

The improved windmill structure, as explained, will form an advantageous acquisition to the art to which it pertains and may be used in connection with all classes of aerial 100

2
motors employing a rotating wheel embodying a series of blades or vanes.

It is proposed to use metals or other substances best adapted for the purpose in the construction of the several parts, and it will be understood that changes in the proportions, dimensions, and minor details may be resorted to without in the least departing from the spirit of the invention.

10 Having thus fully described the invention, what is claimed as new is—

In a windmill, the combination of a shaft, having hub-disks attached to the upper extremity thereof and spaced apart from each 15 other, the disks being provided with rigid radial arms, curved blades hinged to the outer terminals of said arms at points above and below the horizontal centers of the said blades,

depending levers fulcrumed at points intermediate of their lengths to the lower arms 20 and located inside of the inner edges of the blades, said levers having counterpoise-weights adjustably held on their lower extremities, and connecting- rods movably attached to the upper ends of the levers and to 25 the central portions of the sides of the blades, all of the connecting- rods being attached to the same sides of the blades.

In testimony whereof we affix our signatures in presence of two witnesses.

MARVIN A. SHARP.
BIRD H. SHARP.
